ELECTRICAL MUSICAL INSTRUMENT

Laurens Hammond, Chicago, Ill.

Application September 12, 1938, Serial No. 229,447

14 Claims. (Cl. 84—1.26)

My invention relates generally to electrical musical instruments, and more particularly to instruments of this kind which are capable of producing a wide variety of musical tone qualities, similar in musical results obtained, and in the method of playing, to a large well built and voiced pipe organ.

In accordance with the principles of my invention, various tone qualities are produced by combining partials derived from sources of different frequencies corresponding to those of the tempered musical scale. The partials may, however, themselves be complex waves, each comprising a fundamental and a plurality of harmonics, or, each of the partials may consist of 15 impulses of substantially sine wave form. Thus, the player has at his command a method of producing music which approximates very closely that employed in the better pipe organs, but which, in many respects, is superior to the music 20 obtainable from such pipe organs.

It is thus among the objects of my invention to produce an improved electrical musical instrument in which:

(1) Pipe organ like music of a quality superior 25 to that previously obtainable by any known instrument may be obtained;

(2) The electrical impulses are generated by electrical means having no moving parts;

(3) The tones produced will have gradual attack and decay characteristics;

(4) The quality of the tones may be easily varied throughout an exceedingly wide range;

(5) Vibrato and tremolo effects may be produced at will;

(6) Adjustable resonance output circuits may be employed to attenuate certain selected frequency ranges;

(7) Tone qualities may be rapidly selected and varied;

(8) Relatively high voltages are employed in the key circuits, but the major portions of the circuits operate at low potentials;

(9) Key operated switches close circuits of high voltage and low amperage, making practical 45 the use of simple and economical switches;

(10) The harmonic development of the impulses supplied by the generators may be rapidly varied;

(11) Electron discharge devices operating far 50 below their current carrying ratings are utilized for generating the electrical tone frequency impulses as well as for controlling the transmission of these impulses to the output circuits of the instrument, and thus will have a life greatly 55

exceeding their life under normal use in other instrumentalities;

(12) Tones very rich in harmonic development may be produced;

(13) Key switches close very high impedance circuits which may be connected in parallel without appreciable "robbing;"

(14) The transmission of each simple or complex partial to the output circuit is governed by a single control tube and the operation of each control tube is determined by a plurality of high impedance key switch closed circuits, and;

The instrument may be played using customary organ technique to produce music of the organ type far superior to that obtainable by any previous instrument of this class.

A further object is to provide an improved expression pedal apparatus whereby the intensity of notes played on one of the manuals may be changed at will with respect to notes played on the other manual, or with respect to the notes played on the pedal clavier.

Other objects will appear from the following description, reference being had to the accompanying drawings, in which:

Figures 1a and 1b together constitute a schematic wiring diagram of representative portions of the instrument.

Figure 2 is a circuit diagram illustrating a modified form of the invention and incorporating tremulant producing apparatus, and an expression apparatus for each of the manuals as well as for the pedal clavier.

In general, the instrument will comprise a console 35 having two or more manuals, a complete pedal clavier, a plurality of preset keys or tablets for each of the manuals and for the pedal clavier, with or without a piston controlled capture system whereby a plurality of preselected preset keys 40 may be simultaneously selected by operation of the piston in accordance with conventional pipe organ console practice.

The console will also be provided with a vibrato control mechanism whereby the degree of vibrato effect may be regulated, a tremolo controlling means whereby the degree of tremulant, and, if desired, also the frequency of the tremulant may be controlled. In addition, the instrument will be provided with suitable controls for adjustable resonant output circuits by which certain predetermined frequencies may be attenuated.

In addition to the preset keys or tablets by which the instrument may be conditioned to produce predetermined tone qualities, the instrument will preferably be provided with draw bars

or the like, each individually adjustable, to control the relative intensities of the partials of the tone to be produced. Controls will also be provided for rendering the partials from which the various tone qualities may be synthesized rich in harmonic development, or causing them to be of substantially a pure sine wave form. The instrument will be provided with the customary amplifying system and usual means for translating the electrical output of the instrument into sound. The output will, as is customary, be controlled by a swell pedal, operative upon the amplifier to vary its effective gain, or otherwise connected in the output circuit to control the amplitude of the impulses transmitted to the electro-acoustic translating means.

Frequency generating system

While the frequency generating system employed to supply the electrical impulses of the fundamental frequencies of the tempered musical scale might be of any one of a number of different types, I prefer to employ a system in which electron discharge tube oscillators are used to supply the twelve frequencies of the notes of the highest pitch octave of the instrument, and in which each of these oscillators serves as a high frequency source for twelve series of cascaded frequency divider stages. In this system each stage is per se non-oscillatory, but is capable of supplying a signal having a fundamental frequency one-half of that of the regulating frequency which is supplied to it by the next higher stage of the cascaded series, and, with respect to the highest frequency stage, the signal supplied by its associated oscillator. A frequency generating system of this type is fully disclosed and claimed in my co-pending application Serial No. 199,614, filed April 2, 1938, which has matured into Patent No. 2,126,682, granted August 9, 1938.

In its usual form, the instrument will be provided with a plurality of manuals ranging from the musical note C_1 to the note C_8 , while the pedal clavier will range from C_0 to G_2 . For convenience herein, the various notes will be numbered successively, the note C_0 being designated note 1 and note C_8 being designated note 13. In addition to providing means for supplying frequencies for the notes 1 to 13 inclusive, means are provided for supplying frequencies for notes 14 to 96 inclusive, the latter being utilized as partials for notes 38 to 73 inclusive. Thus, although there are no keys corresponding to notes 74 to 96 inclusive, the latter notes are utilized as harmonics in synthesizing notes for which keys are provided, and, if desired, notes 74 to 96 inclusive may be sounded separately by proper manipulation of the draw bars, or by adjustment of the preset key circuits.

As previously stated, the electrical impulses for the twelve highest notes, Nos. 85 to 96 inclusive, are produced by vacuum tube oscillators, the oscillator for note No. 85 being shown in Figure 1a as representative of these twelve oscillators. This oscillator is illustrated as comprising a pair of triodes 100 and 102 which are shown as separate tubes, but in actual practice would ordinarily be combined in the form of a twin triode. The plate of tube 102 is connected through a condenser 104 and resistance 106 with the grid of the tube 100 to provide the feedback, while the frequency of oscillation is controlled by a resonant circuit coupled to the grid of tube 100 and comprising a special high efficiency construction variable inductance

108 and a condenser 110. The frequency of resonance of the oscillatory circuit including the variable inductance 108 and the condenser 110 may be periodically varied by a vibrato mechanism, 5 shown as associated with this circuit and which will hereinafter be described in greater detail. The oscillator for the note 85 provides a signal of a frequency of 4186.01 c. p. s., which is transmitted through a condenser C_a , and a resistor R3 to the control grid 112 of a divider tube DT73 for the note 73.

The divider tube is preferably a pentode with sharp cut-off characteristics, a tube of the type known as 6J7 being satisfactory. The screen and 15 the suppressor grid of the tube DT73 are connected to suitable sources of direct current potential, indicated in Figure 1a as being of +100 v. and +45 v. respectively.

A resistor R4 is connected between the grid 20 112 of tube DT73 and the terminal C of fixed direct current potential illustrated as being of ground potential, the grid being connected to the cathode by a condenser C_b . A condenser C_c connects the cathode to a terminal B likewise indicated as of ground potential, while a resistor R6 connects the cathode to a terminal A of fixed direct current potential indicated as being at -100 v. A resistor R5 connects the plate of tube DT73 to a terminal D indicated as being of +300 v., 25 while the plate is connected to a terminal E of constant direct current potential, indicated as ground, through a condenser C_d . In Figure 1a, the circuit diagram for the first stage only of the frequency divider system is illustrated in detail, 30 since the remaining stages are identical with the stage for note 73 except that the values of the condensers and resistors will vary from stage to stage. In the two lowest frequency stages the circuit may, if desired, be slightly modified as disclosed 35 in my aforesaid Patent No. 2,126,682. The signal from the tube DT73 is derived from voltage fluctuations of its cathode through a condenser C_f which is connected between the cathode and the grid 140 of a control tube CT73.

The stages for the notes Nos. 73, 61, 49, 37, 25, 40 13 and 1 are connected in cascade with the grid of the tube DT73 receiving a signal from the oscillator for note No. 85, and through its plate circuit, transmitting its signal of one-half the frequency of the signal impressed upon its grid to the grid of the divider tube for note No. 61. In this way, each stage of the divider system successively halves the frequency supplied to it, and impresses the halved frequency upon the succeeding stage as a controlling signal. Since the operation of the frequency divider system is fully disclosed and claimed in my aforesaid Patent No. 2,126,682, and since per se it does not form a part of the present invention, the operation of the system will not be further described herein. In so far as the present invention is concerned, any other suitable sources of the frequencies of the various notes of the musical scale might be utilized in 45 place of the divider system shown, provided that such sources are capable of producing signals of the desired wave form and amplitude. The wave is preferably of saw tooth shape, which, when transmitted through the distortion and control tube, provides a signal which may be analyzed into a fundamental and a long series of harmonics of successively decreasing amplitude. While this wave form is preferred, it will be apparent to those skilled in the art that many of the desirable 50 results of the present invention may be obtained

even though the sources produce waves of the simplest character, such as substantially pure sine waves.

Control tubes

Each of the control tubes continuously receives a signal from its associated oscillator or associated stage of the frequency divider system, the signal being impressed upon the grid 140 of the control tube. In the case of the control tubes associated with the oscillator, as, for example, the control tube CT85, the signal is derived from the plate circuit of the triode 100, being conducted through a resistance 144 and condenser 142, the grid 140 of this tube being connected to ground through a resistance 150 which, upon operation of a switch, may have a resistor 148 connected in parallel therewith. In the case of the control tubes connected to the stages of the frequency divider system, of which the control tube CT73 is representative, the signal derived from the cathode of the divider tube DT73 is impressed upon the grid 140 of control tube CT73, and the latter grid is connected to ground through a resistor 152 connected in parallel with a condenser 154. A mute condenser 156 is adapted to be selectively connected in parallel with the resistance 152 and condenser 154 by a suitable switch. The switches which control the connection of the condensers 156 in parallel with the resistance 152 and condenser 154, as well as the switches which are adapted to connect the resistances 148 in parallel with resistances 150, are preferably provided with an actuator which is common to the corresponding switches for all of the notes of the instrument, or, if desired, a plurality of actuators may be provided, each operating a group of these switches. The screen grid 158 of the tube CT73 is suitably connected to a source 160 of adjustable direct current potential, while the suppressor grid 162 may be connected to a similar source, indicated in Figure 1a as ground.

The tube CT73 is normally biased sufficiently beyond cutoff so that it will not transmit the signal which is continuously impressed upon its grid. The control tube is preferably a pentode having sharp cutoff characteristics, such as are found in the type 6C6, which tube has a cutoff voltage of approximately -6 v. Thus, as long as the cathode of the tube CT73 is maintained at a potential of slightly more than +6 v. with respect to ground (since the grid is connected to ground through resistor 152), the tube will remain non-conducting. The amplitude of the signal transmitted by the control tube is determined by the cathode-plate current of this tube, which in turn is controlled by suitable key switch circuits. The cathode-plate current of the control tube may be considered as being "chopped off" by the signal impressed upon its grid. The control of the cathode-plate current of the control tube CT73 is accomplished by means of the key operated switches as follows:

The cathode of the control tube CT73 is connected to a terminal N, which in turn is connected to ground through a condenser C4. The terminal N is connected to a terminal M through a resistor R7, and the condenser C7 connects the terminal M to ground. The resistance of R7 may be in the order of 10,000 ohms. Key operated switches are provided to impress selected potentials upon the terminal M, and because of the resistor R7, the potential impressed upon the terminal M will substantially control the 75

amplitude of the cathode-plate current through the tube CT73.

In the drawings (Figs. 1a and 1b) are illustrated four keys, K-13, K-37, K-61 and K-73 which are representative of the keys of the manuals of the instrument, and are likewise generally representative of the keys of the pedal clavier. Each of these keys when depressed causes its associated switch fingers 170-178 inclusive to be flexed downwardly and make contact with bus bars 180-188 inclusive respectively. Each of the switch fingers 170-178 has one terminal of a resistor 189 connected thereto, the resistor being preferably in close proximity to the switch finger, the other terminal of each of the resistors 189 being connected to one of the terminals M. The resistors 189 are preferably of high value, for example, 500,000 ohms. The wiring system for the key switches may be described briefly as follows:

The switch finger 176 is connected to the terminal M of the control tube generating the fundamental frequency corresponding to that of the key. For example, the switch finger 176 for the key K-73 is connected to the terminal M for control tube CT73. The switch finger 175 is connected to the control tube for the note which has a frequency twice that of the note to which the switch finger 176 is connected, and thus controls the supply of a signal having as its fundamental frequency, the second harmonic of the note of its associated key. Similarly, the switch fingers 174, 173, 172, 171 and 170 control the transmission of frequencies corresponding respectively to the third, fourth, fifth, sixth and eighth harmonics of the note represented by the key with which they are associated. The switch finger 178 controls the transmission of the sub-octave frequency, while the switch finger 177 controls the transmission of a frequency which is the third harmonic of the sub-octave frequency, namely, a frequency substantially 1.5 times that of the fundamental frequency.

The potentials upon the bus bars 180-188 inclusive may be selectively controlled by one of two methods. It will be understood that a separate set of bus bars, such as 180-188, will be provided for each manual and for the pedal clavier, and each set of bus bars will have associated therewith a plurality of preset keys which may conveniently be twelve in number, approximately ten of the preset keys being operable to connect the bus bars 180-188 inclusive to pre-selected direct current potential sources, while two of the preset keys may be utilized to connect the associated bus bars with draw bars by means of which the potential on each of the bus bars may be individually controlled.

In Figure 1b there are illustrated two preset keys PK-1 and PK-10 representative of the group of preset keys by which direct current potentials of pre-selected values may be impressed upon the various bus bars 180-188. Each of the preset keys such as PK-1 and PK-10 is adapted, upon depression, to flex switch arms 190-198 inclusive into contact with bus bars 180-188 inclusive. The switch arms 190-198 inclusive are adapted to be connected by means of conductors 200 with any one of a plurality of conductors 202-210 inclusive. In the instrument the conductors 202-210 may be in the form of bars having a plurality of binding posts to which the conductors 200 may be selectively connected. The conductors 202-210 inclusive are connected

to successive taps on a voltage divider 212 which is supplied with current from a suitable direct current source 214, a protective resistance 216 of suitable value being in series with the voltage divider 212 and voltage source 214 to prevent damage should the voltage divider resistance be accidentally short-circuited. An intermediate tap of the direct current source 214 is preferably grounded so that the conductor 202 is normally at a potential above ground, in the particular construction disclosed, being illustrated at a potential of +6 v.

By way of illustration, the taps of the voltage divider 212, which are connected to the conductors 202-210 inclusive, are indicated as impressing the following voltages upon said conductors respectively: +6, -20, -50, -75, -111, -175, -250, -350 and -500. With these graduations in voltages, the increments in loudness of the notes produced will appear to be substantially equal. The chassis carrying the key switches is preferably connected to the terminal 202 which is at +6 v., so that any current leakage from the key switches will not result in the sounding of a note.

A plurality of draw bars 218 are each provided with a contact making member 220, the draw bars being longitudinally slideable to any desired position of adjustment to bring their respective contactors 220 into contact with contact bars 222-230, which are connected respectively to conductors 202-210 inclusive. The draw bars 218 are connected respectively with switch fingers 190-198 inclusive which are actuated by a preset key PK-11, the connection being made through flexible conductors 232. When the preset key is depressed, and held in depressed position by a suitable latching means, (as shown in my prior Patent No. 1,956,350) it will be apparent that the draw bars 218 will be connected to the bus bars 180-188 inclusive respectively, and that by manipulation of the draw bars, each of the bus bars may be connected to any selected one of the taps of the voltage divider. It will be understood that there will be two or more preset keys similar to the preset key PK-11, and an equal number of sets of draw bars 218 for each manual, and that the pedal clavier is likewise provided with a set of draw bars, although in the case of the pedal clavier, it is not essential that all of the partials be individually controllable as to intensity, and the draw bar system for the pedal clavier may therefore be simplified to the extent desired.

The plate circuits of the control tubes CT1-CT13 inclusive are connected to a common source of B current supply through a conductor 233 and a resistance 234. In the diagram, the plates of all of these tubes are indicated as being connected in parallel. In the actual instrument, the plates will, however, preferably be connected in parallel groups of approximately four notes each, and the common conductor for each group supplied with an adjustable filter pad whereby each group of four notes may be separately voiced to produce the most desirable musical effect. A system of this character is fully disclosed in my Patent No. 2,126,464, dated August 9, 1938.

In the simplified circuit disclosed herein, the signals from the control tubes are fed through conductor 233 and condenser 238 to adjustable resonant output circuits 236, and the signal is fed from the resonant output circuits to a volume or expression control and adjustable tremulant

device 240, the latter being resistance-coupled through a preamplifier 242 and power amplifier 244 to a loud speaker system 246, the preamplifier and power amplifier being, as is customary, supplied with current from a suitable power supply system.

Vibrato producing means

The effectiveness of musical tones is, generally speaking, greatly enhanced for certain purposes, by causing its frequency to shift over a limited range at a periodicity of 6 or 7 c. p. s. In the instrument of my invention, means for producing such vibrato frequency shift comprises a plurality of condensers 248 which, by means of switches 250, may selectively be connected in parallel with a portion of inductance 108. There is a set of condensers 248 for each of the twelve oscillators and the corresponding switches 250 of each of the oscillators are mechanically interconnected for simultaneous operation.

Two of the condensers 248 are adapted to have one of their plates grounded through a switch 252 which completes a circuit through a vibrating reed 254. There may be six reeds 254 (of which only two are illustrated) and each is vibrated at a slightly different frequency, being actuated by an electromagnet 256 which is energized from a suitable source of current through an interrupter circuit completed through the reed during a portion of the oscillatory cycle of the latter. By having the reeds 254 tuned to slightly different frequencies, all close to 7 c. p. s., six slightly different vibrato frequencies will be impressed upon the twelve oscillators. By connecting oscillators for adjacent semi-tones to the same reed, most of the notes of a chord normally sounded during playing customary music will have a different vibrato frequency, since it is rather the exception to have a chord include adjacent semi-tones or notes separated by an octave plus or minus a semi-tone.

The values of the condensers 248 which have one side thereof permanently connected to ground are such, with respect to their associated condensers, that upon changing the positions of the switches 250, the average frequency of the associated oscillator will not be altered. By having the condensers 248 connected in parallel with only a portion of the inductance 108, the condensers 248 may be made of greater capacitances so that the distributed capacity of the wires and switches connected to these condensers will be small relative to the values of the condensers, and thus have but a negligible effect.

The vibrato mechanism is more fully disclosed and claimed in my co-pending application Serial No. 199,612, filed April 2, 1938.

Operation

The instrument is operated in the manner of an organ and is capable of rendering, with a high degree of satisfaction, the classical works of organ literature.

After depressing the desired preset key, assuming the supply of power has been connected to the oscillators, frequency dividers and amplifiers, the instrument may be played in the usual manner by depressing the playing keys K1-K13. Upon depression of a key, for example, K31, the potentials of terminals M associated with the control tubes for the frequencies which are partials of the note 31 will each be changed rather gradually to the potential of the bus bar 180-188 to which the terminal is connected.

Due to the relative impedances of the resistors

189 and the resistances R7, the fact that a single terminal M may be connected to a plurality of different bus bars through the different key switch circuits is not appreciably disadvantageous. This may be shown by computing the current flow through the resistor R7 under several different conditions of operation, since it is the current flow through the resistance R7 which determines the amplitude of the output signal of the control tube.

For example, let us assume that the cutoff voltage of the control tube is 6 volts and that the terminal M is connected through only one key switch circuit to a bus bar, the potential of which is -500 volts, making the potential difference which causes current to flow through the resistors 189 and R7, 506 volts. Since the total resistance of this circuit is 510,000 ohms, the current flow (after a steady state has been attained) will be .993 ma.

As a further example, let us assume that the terminal M is connected through two key switch circuits to two bus bars, one having a potential of -500 volts, and the other having a potential of -6 volts. It may readily be computed that under these conditions, the current flow through the resistor R7 will amount to .975 ma.

As a further example, let us assume that a terminal M is connected through two key switch circuits to two bus bars, each of a potential of -500 volts. Under these circumstances the current flow through the resistor R7 will amount to 1.950 ma.

From the three foregoing examples, it will be seen that the current flow through resistance R7, and hence the amplitude of the signal, is reduced only from .993 ma. to .975 ma. when the terminal M is not only connected to a bus bar of -500 volts, but in addition is connected to a bus bar of -6 volts. The undesired reduction in the amplitude of the signal under these circumstances is thus less than 1.85%, a reduction in amplitude which would not be perceptible to the normal ear.

Similarly, when the terminal M is connected through two key switch circuits to two bus bars, each of -500 volts, the current flow through resistor R7 will be 1.950 ma., whereas it should, strictly speaking, be $2 \times .993$ ma., or 1.986 ma. The reduction in amplitude of the signal is thus again less than 1.85%, which is imperceptible to the ear. Of course under extreme conditions, when a terminal M is connected to a large plurality of bus bars of different potentials, the reduction in amplitude of the signal due to the "robbing" effect may be greater, but this will occur only when playing a chord having a large number of harmonically related notes. Under these circumstances it is not disadvantageous that some "robbing" takes place. The musician is accustomed to this effect because it takes place whenever a plurality of organ pipes of the same pitch are sounded simultaneously, or whenever a plurality of instruments play the same note, since there is a certain amount of interference between the partials of the several sound producing bodies, so that there is never a true arithmetical addition of the amplitudes of the partials. This effect is of course obvious when it is considered that there is practically no possibility whatsoever that partials of the same frequency produced by different sources will be exactly in phase, and there will therefore be some cancellation of the partials from one source by the partials produced by the other sources.

The tones produced will have a quality which will be dependent upon the various voltages on the bus bars 180-188 as determined by the particular preset key which has been operated. The tone may be made of relatively simple character by holding the reeds 254 against vibration by any suitable vibrato controlling means and by closing the switches which connect the condensers 156 in parallel with the condensers 154. If it is desired to render the tone more complex, the switches for the condensers 156 may be opened, whereupon the signal from each of the control tubes will in itself contain a large number of partials so that the musical effect will be that obtained by the sounding of a plurality of organ pipes or the like. Since, speaking generally, the trained musical ear prefers a tone in which the acoustic energy is distributed over a wide range of frequencies, it will be apparent that under these circumstances a beautiful, rich and full tone will be produced.

The warmth of the tone may be increased by rendering the vibrato mechanism operative. The vibrato mechanism has the effect of adding further richness to the tone since it adds new and different frequencies. As previously stated, there are preferably six different vibrato rates since the reeds vibrate at slightly different frequencies. Thus, when a plurality of notes are being simultaneously sounded they will be shifting in frequency at different rates in a substantially random manner, so that the musical effect will be an increase in the warmth, fullness and richness of the tone rather than the effect of a definite vibrato or tremolo. There will be so many changes in the frequencies going on simultaneously that the ear is unable to analyze the various changes in tone which are occurring, and the listener thus obtains only the aggregate impression of a beautiful satisfying tone quality. Of course the degree of vibrato effect may be varied in any one of three gradations by optional operation of the switches 250.

When the player desires to produce a tone which is not available on depression of one of the preset keys PK-1 to PK-10, he will utilize the draw bars 218 to pre-select the tone quality, rendering the draw bars effective by depression of an associated draw bar control key, such as PK-11. With the draw bar control, the musician may select any one of myriads of tone colors, merely by setting the draw bars to the desired one of countless possible combinations.

In order to prevent short circuiting of the battery 214, or short circuiting one or more sections of the voltage divider resistance 212, means (such as are well known in adding machine keyboard construction), are preferably provided to prevent the simultaneous depression of more than one of the preset keys associated with a given manual or pedal clavier. However, even if two or more preset keys were simultaneously depressed, and by such action the entire voltage divider resistance 212 was short circuited, no serious injury to the battery 214 would result, due to the provision of the protective resistance 216.

The preselected tone qualities produced upon depression of one of the preset keys PK-1 to PK-10 may, of course, be changed by the user of the instrument merely by changing the connections of the conductors 200 with the conductors 202-210, so that any particular tone quality found especially pleasing to the musician may be rendered instantly available, merely by the depression of the particular preset key upon

which this preferred tone quality has been set up.

The output signals of the control tubes may be transmitted to either one or a plurality of adjustable resonant output circuits such as are disclosed in greater detail in my aforesaid Patent No. 2,126,464. The over-all output may, of course, be controlled by the usual swell pedal and by a suitable tremulant device.

Modified expression control apparatus

In the foregoing description, it has been indicated that the preset keys for both manuals and the pedal clavier may have their switch fingers connectable to the same set of conductors 202-210. With this type of circuit only the over-all volume of notes played on both manuals and the pedal clavier may be controlled by means of the volume control 240. Similarly, the tremulant included with the volume control 240 will be operative for notes played upon any keyboard of the instrument. The variety of expression obtainable from the instrument may be increased considerably if the musician has available means for controlling separately the intensities of notes played upon different keyboards. Thus, the melody of a musical selection may be played upon one manual at a relatively high intensity, while the accompaniment may be played upon the other manual at a lower intensity. In Figure 2 is illustrated a circuit by means of which such divided expression may be obtained.

In this figure a common source of direct current potential 250 may be employed to supply three tapped voltage divider resistances 252, 254, 256 for the upper manual, lower manual and pedal clavier respectively. Each of these voltage divider resistances may be similar to the voltage divider 212 previously described. The voltage divider 252 for the upper manual has the potential impressed across its terminal controlled by means of a variable resistor 258 having a sliding contact 260. The contact 260 may be operated by the usual expression pedal for the upper manual in a well known manner.

The resistance 258 is connected to one terminal of the voltage divider resistance 252 through an adjustable resistance 262 which is adapted to be shunted by a circuit including a switch 264 which is operated by means of a cam 266 which is continuously rotated at a tremulant frequency. A condenser 268 is connected in parallel with the voltage divider resistance 252 so as to prevent the introduction of high frequency transients upon the periodic opening and closing of the switch 264.

The degree of effectiveness of the tremulant device is of course controlled by adjustment of the variable resistance 262. The taps of the voltage divider resistance 252 are connected to conductors 272-280 inclusive which form the different potential sources to which the switch fingers of the preset keys PK may be selectively connected in a manner as previously described with respect to Figure 1b. Similarly, the draw bars 218 and their associated preset key may be provided to selectively connect the conductors 272-280 to the bus bars 290-298 inclusive. Of course there may be two or more sets of draw bars, each controlled by a separate preset key, but operating in the same way selectively to adjust the potentials on the bus bars 290-298.

The expression device for the lower manual may be identical with that for the upper manual and is thus illustrated, and the same reference

characters have therefore been applied to the corresponding parts except that the sliding contact of the adjustable resistance 258 for the lower manual has the reference character 261 applied thereto. It will be noted also that the variable resistance 258 for the two manuals do not have their corresponding ends connected in the circuit. This is to illustrate the fact that although ordinarily each of the sliding contacts 260 and 261 will be connected for independent operation by an associated expression pedal, they may, if desired, be connected to a common actuating means, in which event they are preferably connected so that increasing the potential across the voltage divider 252 for the upper manual will cause a corresponding decrease in the potential across the voltage divider 254 for the lower manual and vice versa. In this way, a common pedal might be used as a simple means for determining the relative intensities of the notes upon the two manuals. It will of course be understood that if more than two manuals are provided, an additional voltage divider and associated set of circuits will be provided for each additional manual and in that event, a separate expression pedal will ordinarily be provided for each of the manuals.

It will ordinarily be undesirable to provide a tremulant device for the notes played on the pedal clavier, and the voltage divider resistance 256 for the pedal clavier is therefore illustrated as having its potential controlled only by the variable resistance 258. The sliding contact 263 is connected to the sliding contacts 260 and 261 through a common conductor which is connected to the negative terminal of the source of direct current potential through a protective resistance 267. The adjustable slider 263 may, if desired, be controlled by means of a separate expression pedal, or may be manually controlled. The cams 266 for the tremulant switches 264 may be driven by a small motor through suitable speed reducing gearing, the motor, or the gearing, preferably having a speed control so that the tremulant rate may be adjusted.

With the controls shown in Figure 2, the musician may conveniently balance the intensity of the tones of one manual against those of the other manual or pedal clavier so as to obtain a great variety of expression. When the circuit of Figure 2 is utilized in conjunction with that shown in Figures 1a and 1b, the tremulant device indicated as associated with the volume control 240 may be rendered inoperative whenever the tremulant devices 262, 264, 266 and 268 are in use.

Due to the relative values of the resistors 189 and R7 and the condenser C1, the individual notes produced will have a gradual attack characteristic. Since there will be a charge upon the condenser C1 after the key is released, the note will continue sounding as the condenser C1 discharges through the resistance R7, and thus the decay of the note will be at a logarithmic rate. Of course the condenser C1 could be variable, or there may be provided additional condensers which could optionally be connected in shunt with the condensers C1, thereby decreasing the rates of attack and decay of the notes.

It will be apparent to those skilled in the art that very many changes of a similar character could be made in the instrument without departing from the underlying principles of the invention.

It will be understood that the reference to batteries herein is intended to mean suitable

sources of direct current, and that the instrument will be provided with a suitable power supply system which may be a common source for supplying energy to all of the circuits, or that several of such systems or sources of current may be utilized.

It will be further understood that the values of the electrical elements utilized in the instrument given herein are intended to be illustrative only, and that there may be considerable variation in these values without appreciably affecting the results obtained, particularly if compensatory changes are made in the values of other elements. I therefore intend by the following claims to include within the scope of my invention all such similar constructions and circuits whereby substantially the results of my invention, of which merely an illustrative embodiment is disclosed herein, may be obtained in substantially the same way.

I claim:

1. In an electrical musical instrument having a plurality of terminals, the direct current potentials of which determine the intensity at which the notes of the musical scale are sounded, keying circuits for determining the direct current potentials of said terminals comprising, a plurality of sources of direct current potential of graduated voltage, a plurality of keys, a plurality of switches operated by each of said keys, each of said switches having a pair of contacts, a high resistance connection from one contact of each of said switches to one of said terminals, there being a plurality of said high resistance connections between the contacts of a plurality of said switches respectively and a single one of said terminals, and selectively operable means to determine the direct current potentials of the other contacts of said switches by selective connection to said sources.

2. The combination set forth in claim 1, in which said high resistance connection includes a resistor physically adjacent the switch contact to which it is connected.

3. In an electrical musical instrument having a plurality of terminals, the direct current potentials of which determine the intensities at which notes of the fundamental frequency of the musical scale are sounded, keying circuits for determining the direct current potentials of said terminals, comprising a plurality of keys, a plurality of switches operated by said keys, each of said switches having a pair of contacts, a high resistance connection from one contact of each of said switches to one of said terminals, there being a plurality of said high resistance connections between the contacts of a plurality of said switches respectively and a single one of said terminals and a plurality of selectively operable keys effective upon actuation to determine the direct current potentials of the other contacts of said switches.

4. In an electrical musical instrument in which the sound is originated electrically by a plurality of generators, each generating a signal having a fundamental frequency corresponding to that of a note of the musical scale, and in which the intensity of the signal transmitted from each of said generators to the output of the instrument is determined by the direct current potential of a terminal associated particularly with such generator, the combination of a plurality of sources of direct current potential of different values, a plurality of bus bars, means for selectively connecting said bus bars to said sources, a plurality

of keys, a plurality of switch fingers operated by each of said keys, said switch fingers being operable to contact with said bus bars respectively upon operation of the keys, and a high value resistor connected between each of said switch fingers and one of said terminals, each of said resistors being individual to its associated switch finger.

5. In an electrical musical instrument in which the sound is originated electrically by a plurality of generators, each generating a signal having a fundamental frequency corresponding to that of a note of the musical scale, and in which the intensity of the signal from each of said generators which is transmitted to the output of the instrument is determined by the direct current potential of a terminal associated particularly with each of said generators, the combination of a source of direct current potential, a voltage di-

vider connected to said source and having a plurality of taps of different potential, a plurality of bus bars, means for selectively connecting said bus bars to said voltage divider taps, a plurality of keys, a plurality of switch fingers operated by each of said keys, said switch fingers being operable to contact with said bus bars respectively upon operation of the keys, and a resistor individual to each of said switch fingers and connected between its associated switch finger and one of said terminals.

6. In an electrical musical instrument in which signals having fundamental frequencies corresponding to the notes of the musical scale are electrically generated and translated into sound, each under the control of a device having a terminal, the direct current potential of which determines the intensity of the signal transmitted to the translating means, the combination of a plurality of sources of graduated direct current potential, a plurality of keys, a plurality of switches operated by each of said keys, and a plurality of high impedance circuits individual to said switches, effective upon depression of said keys to connect said sources respectively with said terminals.

7. In an electrical musical instrument in which signals having fundamental frequencies corresponding to the notes of the musical scale are electrically generated and translated into sound, each under the control of a device having a terminal, the direct current potential of which determines the intensity of the signal transmitted to the translating means, the combination of a plurality of sources of graduated direct current potential, a plurality of keys, a plurality of bus bars, a plurality of switches operated by each of said keys, separate high impedance circuits to connect said bus bars respectively with said terminals respectively upon closure of said switches, and a plurality of manually adjustable contactors each connected to one of said sources and operable to connect its associated source to a selected bus bar.

8. In an electrical musical instrument having electroacoustic translating means, the combination of a generator of a signal having a fundamental frequency of a note of the musical scale, an electron discharge device for controlling the transmission of said signal to said translating means, the effectiveness of said electron discharge device in transmitting said signal being determined by the current flow through a resistor, and a plurality of key circuits for controlling the current flow through said resistor, each of said key circuits including a key operated

switch, a high resistance element connected between said switch and said resistor, and a plurality of direct current potential sources of graduated value arranged to be connected in series with said resistance elements respectively by said key operated switches, thereby to determine the current flow through said resistor.

9. In an electrical musical instrument having a plurality of generators of electrical signals having fundamental frequencies corresponding to the notes of the musical scale, electroacoustic translating means, and a device for controlling the transmission of signals from said generators to said translating means, the intensity of the note sounded by said translating means being determined by the direct current potential of a terminal forming part of each of said devices, the combination of a plurality of sources of direct current of graduated potential, a plurality of selectively closable circuits between each of said terminals and said sources, each of said circuits including an impedance individual to it and of value which is high with respect to the impedance of that portion of said device which receives current from said terminal.

10. In an electrical musical instrument having a plurality of manuals in which the intensity of

the notes sounded upon depression of the keys of each manual is determined by the direct current potentials impressed upon bus bars associated with that manual, a voltage divider for each of said manuals for supplying direct current to the bus bars thereof, a source of direct current connected to each of said voltage dividers, and a variable impedance device connected to each of said voltage dividers for selectively changing the potential across its terminals.

11. The combination set forth in claim 10, in which an expression pedal is provided for the operation of each of said devices.

12. The combination set forth in claim 10 in which a single expression pedal is provided for the operation of both of said devices.

13. The combination set forth in claim 10 in which a single expression pedal is provided for said devices and is operable to progressively increase the potential across the terminals of one of said voltage dividers while progressively decreasing the potential across the other of said voltage dividers.

14. The combination set forth in claim 10 in which a protective resistance is connected in series with each of said voltage dividers.

LAURENS HAMMOND.
